Claims priority, application Great Britain Aug. 19, 1959
5 Claims. (Cl. 333—96)

This invention relates to wave energy modulating arrangements and more specifically to modulating arrangements of the kind in which very high frequency wave energy is modulated by propagating it along a waveguide in which is a ferrite or similar body and subjecting said body to a modulated or varied magnetic field produced by a coil system outside the guide.

The object of the invention is to provide improved, simple and efficient modulating arrangements of the kind referred to wherein, despite that the coil system is outside the waveguide, there is minimum losses due to the interposition of the walls of the guide in the path of the magnetic flux and minimum interference with the proper functioning of the waveguide as such.

It is common practice to effect modulation of a high frequency electro-magnetic wave transmitted down a waveguide by applying a magnetic field which is varied in accordance with modulation to vary the magnetisation of a ferrite body inserted in the waveguide, the modulating magnetic field being generated by a coil system outside the guide. One of the difficulties met with in modulators of this nature is that, since the varying magnetic field has to pass through the guide walls to reach the ferrite body, it induces substantial eddy currents in said walls, especially if the modulating frequencies are relatively high. These eddy currents of course constitute loss and tend in effect to short circuit the magnetic field and oppose proper and efficient modulation. Various expedients have been proposed to meet this difficulty but it is by no means easy to do so without interfering with the proper functioning of the waveguide as such, and without resulting in a structure which is mechanically unsatisfactory or unduly expensive or incapable of handling high power. For example, it has been proposed to use a guide in the form of a very thin film of deposited silver or aluminium on the inside of an insulating tube, but this construction will not handle high power satisfactorily and is, moreover, expensive and mechanically weak. It has also been proposed to slot the waveguide with a slot running parallel to the axis, but here again such a slot tends to distort the field, its provision results in an asymmetrical waveguide and leakage of high frequency (microwave) energy tends to occur through the slot. Another proposal which has been made is to provide the waveguide with a helical slot, the slotted waveguide being formed by electro-forming it on a special mandrel and then using the coil, which the slotted guide in fact constitutes, as the source of the modulating magnetic field. This expedient avoids the difficulty above mentioned by in fact dispensing with the external modulating field source altogether (since the guide itself is now the field source) but the construction is expensive and again there is a tendency to microwave energy loss through the helical slot. There is also an added limitation in design parameters because of the fact that the magnetisation coil and the guide are now one and the same.

According to this invention an arrangement of the kind referred to for modulating very high frequency electro-magnetic wave energy comprises a length of waveguide constituted by a helically wound metallic tape with the edges of the turns substantially in physical contact with one another but insulated from one another, a ferrite body

2

within said length of waveguide and a winding external to said length of waveguide and arranged and adapted to provide a varying magnetic field through said body to modulate, in accordance with the variations of said field, high frequency wave energy transmitted through said length of guide.

Preferably the tape is aluminium tape anodised to provide the insulation between the turns.

In order to reduce discontinuities between the helically wound length of guide and the adjoining ends of waveguides between which the length is inserted to form a "run" of guide, it is most desirable, if not essential, that the ends of the helically wound length be finished flat, i.e. that they terminate in planes at right angles to the axis. One way of doing this is to fit each end of the helically wound length with a cylindrical collar which is flat at one end and shaped with a step at the other to mate with the end of the helix proper, the tape of which is cut off square to the length of the tape. Another way is to solder together the last few turns of the helical guide to permit it to be turned off square, i.e. flat.

Preferably also the outside of said length of guide is covered with a thickness of comparatively rigid insulating material, e.g. resin, and the winding is positioned on the outside of this insulating material. In one construction, the winding is a single layer winding of turns of conductive tape wound directly on the insulating material.

The ends of the length of waveguide may be fitted with flanges which must be so arranged that, when said length is inserted in a "run" of guide, it is insulated at least at one end from the adjacent guides. Accordingly, if a flange on the end of the helically wound length is to be in metal to metal contact with a flange at the end of an adjacent length of guide, the former flange should be insulated from the helix and a thin insulating shim is inserted to avoid contact between the end of the helix and the adjacent guide.

The invention is illustrated in the accompanying drawing which is a simplified sectional view of a preferred embodiment of the invention as applied to a frequency or phase modulator of microwave energy. Although the invention is not limited to its use at any particular band of frequencies, it is very advantageous for phase or frequency modulation of microwave energy at comparatively high frequencies and the illustrated embodiment is suitable for use for phase or frequency modulating microwave energy of a frequency of the order of 10,000 mc./s. by a modulating frequency of the order of 1 mc./s. Practical principal dimensions for the illustrated embodiment when intended for the frequencies stated are: about 9½" overall length and about 0.81" for the inside diameter of the guide, the guide being wound from anodised aluminium tape about $\frac{1}{16}$ of an inch wide and about $\frac{1}{32}$ of an inch thick.

Referring to the drawing, a circularly sectioned guide 1 is made from anodised aluminium tape which is wound in helical form with the edges of the turns in contact with one another as indicated by the parallel lines 1^a shown at the ends of the guide length. It will be understood that the distance between any two adjacent parallel lines 1^a represents the width of the tape. The anodising of the aluminium provides insulation so that although the tape edges are physically in contact with one another and the finished guide has no gaps or substantially no gaps leading to the exterior, the turns are effectively insulated each from the next. The ends of the wound guide are finished off by flanges which serve for coupling the length of guide to other guide lengths (not shown). These flanges should be insulated from the guide proper and may be fitted thereto in any convenient manner. The most practical way of making the guide consists in winding the tape

on to a mandrel so that no gaps occur in the winding; clamping it at the ends; and then, after trimming the ends if necessary, fitting the flanges in position with suitable insulation between them and the guide proper. The clamps may then be removed and the mandrel punched out.

In the illustrated embodiment the waveguide with its end flanges, which are marked 2, is "potted" with resin or some other suitable insulating compound so that the guide is externally coated to provide it with additional mechanical strength and rigidity by a comparatively thick layer of resin or other insulating compound 3. On this layer is wound the modulating magnetizing coil which is conventionally represented at 4 and may conveniently consist in practice of a few turns of copper tape wound directly on to the insulation 3. The coil 4 extends at least over the length of a ferrite insert which is shown as of conventional form at 5, i.e. it is a ferrite rod with pointed ends for avoiding sharp impedance discontinuities. The ferrite rod 5 is supported in position in the guide by suitable insulating supports 6, preferably apertured as indicated.

An experimental arrangement as illustrated using anodised aluminium tape 0.1" x 0.032" has been successfully used at the frequencies hereinbefore mentioned to handle 500 watts C.W. power.

I claim:

1. A wave energy modulating arrangement in which very high frequency energy is modulated comprising a length of waveguide, a ferrite body located in said waveguide, a magnetic coil positioned outside said length of waveguide arranged and adapted to subject said body to a modulated magnetic field, said waveguide being of circular cross-section and comprising a helically wound alumin-

ium tape the turns of which are substantially in physical contact with one another, said tape being anodised to provide insulation between the turns whereby energy transmitted through said length of waveguide is modulated by the varying magnetic field through said body.

- 5 2. An arrangement as claimed in claim 1 wherein the ends of the helically wound waveguide terminate in planes at right angles to the guide axis and wherein the last few turns of said tape are soldered together.
- 10 3. An arrangement as claimed in claim 1 wherein the said guide is covered with a layer of insulating material and wherein said coil is positioned on the outside of said insulating material.
- 15 4. An arrangement as claimed in claim 1 wherein each end of the helically wound length is fitted with a cylindrical collar which is flat at one end and shaped with a step at the other to mate with the end of the helix proper, the tape of which is cut off square to the length of the tape.
- 20 5. An arrangement as claimed in claim 1 in which said waveguide length is fitted at least at one end with a flange insulated from the helical winding.
